**REGISTER CONTROL FOR ROTARY
PRINTING PRESS**

Clarence L. Hornberger, Lancaster, Pa., assignor to
Armstrong Cork Company, Lancaster, Pa., a corpora-
tion of Pennsylvania

Filed Aug. 29, 1961, Ser. No. 134,685
5 Claims. (Cl. 101—248)

The present invention relates broadly to rotary printing and more particularly to a rotary printing press and system adapted to manufacture gravure-printed floor coverings or the like.

More specifically, the present invention relates to off-set gravure printing of a rotary character having extremely high operating features, high quality of end product produced, and providing for optimum working conditions.

It has been found that when printing designs on felt rug bases and the like, and which design necessitates a plurality of colors in ink, off-set gravure printing results in favorable working conditions and optimum quality in the end product. While flat bed and/or direct gravure presses have heretofore been utilized, certain limitations as to the design which could be printed or undesirable operating characteristics of the machine have been inherent therein.

It is accordingly a principal object of the present invention to provide a rotary press of an off-set gravure type for printing of designs in ink on felt base to produce a printed rug which overcomes the drawbacks and unsatisfactory characteristics of previously known devices.

The principle involved in use of a press of the character of the present invention involves depositing various colored inks in proper position on a continuously moving web by rotating cylinders. Considered broadly, three such rotating cylinders are involved in placing any one color, and when properly assembled with relationship to a driving means and a means of transporting the web through an ink drying area, they constitute one stand of the over-all press and press system. As contemplated by the present invention, the entire press can consist of a plurality such as five of these printing stands spaced from one another along a continuous line. Another principal object of the present invention is to provide apparatus and a system such that removal and/or replacement of various of these cylinders can be effected easily and quickly with a minimum of effort, and with a minimum possibility of damage to the rolls. As will appear hereinafter only two of the rolls in any one stand need be changed for such purposes as change of design to be printed and/or damage or wear of the rolls. The construction and arrangement of the present invention is such that these two rolls namely, the off-set and engraved cylinders in any stand of the press can be removed vertically from the machine by means of a single overhead crane and removed to a cylinder cleaning station and rack removed from the work area or space. This is possible due to the arrangement and mounting of the rolls. This arrangement and mode of operation negate the necessity of moving the rolls laterally out from the stand for placement on dollies or the like with a possibility of damage to the rolls and to operating personnel while at the same time greatly decreasing the time required for such a change-over.

Another important object of the present invention is to provide in a rotary off-set gravure printing press a mounting and arrangement of the rolls such that any individual stand in the press may be rendered inactive by movement of solely the off-set cylinder or roll to inoperative position without in any way affecting the tension on the web

2

so that proper registry is maintained at all times due to a constant tension on the web even with one of the stands in inoperative condition.

Another object of the present invention is to provide in such a press an arrangement of the cylinders or rolls such that the off-set cylinder can be easily and readily replaced by a flexographic roll and permit a flexographic printing for certain types of designs and/or over-printed borders.

A still further object of the present invention is to provide in such a press a mounting and control of the off-set cylinder such that it can, in any desired stand, be selectively raised or lowered to inactive and active positions and so timed with the remainder of the over-all press as to effect a skip printing which is particularly suitable for cross border printing, and such operation will not affect in any way the operation of the remainder of the press.

An additional object of the present invention is to provide in a press of the character described, a novel doctor blade holder susceptible of so mounting and being driven as to be substantially trouble free, susceptible of easy mounting and operation, and removal vertically from a stand of the press.

An additional object of the present invention is to provide in a press system of the character described, an arrangement whereby the web to be printed is so disposed and led through the apparatus as to provide easy access to the mechanism and permit removal of the off-set and engraved cylinders as also the doctor blade and holder from overhead without interfering with the web, and additionally permits maintaining tension on the web with the off-set cylinder raised to inoperative position or removed for replacement.

A still further object of the invention is to provide a press in which the off-set cylinder can be moved to inoperative position without affecting the position of the impression or engraved cylinders while maintaining constant rotation of the off-set cylinder so as to maintain proper registry of the various cylinders.

A further object of the present invention is to provide in a printing press arrangement mounting and interconnecting drive means permitting of adjustment of the rolls for proper pressure relationships and registry.

Additional objects, features and advantages of the present invention will be more readily apparent from the following detailed description of an embodiment thereof when taken together with the accompanying drawings in which:

FIGS. 1a and 1b are complementary schematic elevational views illustrating the subject invention in a typical plant installation embodying a multi-unit press set-up;

FIG. 2 is an enlarged fragmentary plan view as viewed from line 2—2 FIGS. 1a and 1b respectively illustrating the drive arrangement between the various components;

FIG. 3 is a transverse section as viewed from line 3—3 of FIG. 1a, of the transport system for facilitating press cylinder changes and servicing;

FIGS. 4 and 5 are enlarged fragmentary end and side elevations of a press cylinder and associated bearing in course of transit;

FIG. 6 is a fragmentary sectional view on the line 6—6 of FIG. 2, of the infeed tension stand;

FIG. 6a is a similar view on line 6a—6a of the outfeed tension stand;

FIG. 7 is a fragmentary schematic on line 7—7 of FIG. 6 showing details common to both infeed and outfeed stands;

FIG. 8 is a side elevational view of one of the press units with associated dryer section;

FIGS. 9a and 9b are complementary front elevational views of the press unit;

FIG. 10 is a vertical elevation through the press and associated dryer section as viewed from line 10—10, FIG. 9a;

FIG. 11 is a fragmentary enlargement of a portion of FIG. 10;

FIG. 12 is a fragmentary section on line 12—12 of FIG. 10;

FIGS. 13a and 13b are complementary plan views of the press section as viewed from line 13—13, FIG. 8;

FIG. 14 is a schematic sectional plan more clearly illustrating certain of the detail appearing FIG. 13a;

FIG. 15 is a section on line 15—15, FIG. 14;

FIG. 16 is a fragmentary elevation showing the adaptation of a modified form of printing cylinder; 15

FIG. 17 is a vertical section on line 17—17, FIG. 13a illustrating details of a timing device used during activation of off-set cylinder;

FIG. 18 is a section on line 18—18, FIG. 17;

FIG. 19 is an enlarged side elevation of the press section with the side frame cover plate removed;

FIG. 20 is a view with the side frame deleted and showing certain parts of FIG. 19 in an adjusted position;

FIG. 21 is a fragmentary transverse section on line 21—21 of FIG. 19, showing the blotting roll mounting and associated mechanism;

FIG. 22 is a fragmentary vertical section on line 22—22 of FIG. 19 showing details of the off-set cylinder bearing mount;

FIG. 23 is a transverse section on line 23—23, FIG. 22;

FIG. 24 is a fragmentary section on line 24—24 of FIG. 19, showing certain of the mechanism associated with the impression cylinder;

FIG. 25 is a fragmentary enlargement as viewed from the line 25—25, FIG. 24 showing the impression cylinder latching mechanism;

FIG. 26 is a transverse section on line 26—26, FIG. 25;

FIG. 27 is a fragmentary section on line 27—27, FIG. 25;

FIGS. 28 and 29 are perspective views of certain details of the latching mechanism;

FIGS. 30a and 30b are complementary vertical sections as viewed on the line 30—30, FIG. 8, illustrating details associated with the off-set printing cylinder mounting;

FIGS. 31 and 32 are perspective views of mounting elements;

FIG. 33 is a vertical section on line 33—33, FIG. 30a; 50

FIGS. 34, 35 and 36 are similar views taken on the lines 34—34, 35—35, and 36—36 respectively of FIG. 30b;

FIG. 37 is a vertical section through the shaft coupling shown in FIG. 30b;

FIG. 38 is a vertical sectional view taken on line 38—38 of FIG. 9b, through the press drive transmission;

FIG. 39 is a transverse section on line 39—39, FIG. 38;

FIG. 40 is a fragmentary section on line 40—40, FIG. 38;

FIG. 41 is a fragmentary plan as viewed from line 41—41 of FIG. 38;

FIG. 42 is a fragmentary elevation as viewed from the line 42—42, FIG. 40;

FIG. 43 is a fragmentary sectional plan on line 43—43 of FIG. 9b, showing further details of a declutching mechanism;

FIG. 44 is an elevation as viewed from the line 44—44, FIG. 43;

FIG. 45 is an enlarged vertical section through the doctor blade drive appearing in FIG. 38;

FIG. 46 is a vertical section on line 46—46, FIG. 45; 70

FIG. 47 is a view in plan of FIG. 46;

FIG. 48 is a fragmentary plan of the front end of the press section illustrating details of the doctor blade and associated mechanism;

FIG. 49 is a vertical section on line 49—49 of FIG. 48;

FIG. 50 is a similar section on line 50—50, FIG. 48; FIGS. 51a and 51b are enlarged complementary sectional views on the line 51—51, FIG. 49, showing details of the doctor blade mounting;

FIG. 52 is a further enlarged fragmentary section on the line 52—52, FIG. 51b; and

FIG. 53 is a showing in perspective of the blade mounting elements.

The invention will now be described with reference to the drawings as applied to a rotary off-set gravure printing system adapted to print a plurality of colors into a pattern on a travelling web of felt or the like to create a finished felt base floor rug. Only such parts as are necessary to a full and complete understanding of the invention have been set forth in the drawings and will be described in detail hereinafter. Details of construction which are well within the scope of those skilled in the art will not be described, or are not shown in detail for purposes of clarity.

Referring to FIGS. 1a and 1b, which are complementary schematic elevational views illustrating a typical plant installation embodying the present invention, a plurality of press units are utilized in a production line, each of which is adapted to print one color onto a web or otherwise effect a working operation on the web as will appear more clearly hereinafter. In the drawings, five press units A, B, C, D, and E are shown although it is to be understood that any desired number of units may be used according to the number of colors or operations desired.

Each of these press units constitutes an off-set gravure press together with the requisite inking and control mechanism, web guiding mechanism, drying chamber, and other features which will be disclosed more fully hereinafter. Each of the press units is connected to a single driving means connected to a suitable power means and interconnecting drive means to the common driving means.

Referring to the figures more in detail, a web 1 which can consist of any usual or known type of material but preferably a felt base, is shown as being threaded through various mechanisms constituting the production line and including the various press units. The web is initially drawn from preformed rolls 2 mounted on unwind stand 3 which as seen consists of a double mount stand to facilitate the continuous running operation and to have available a ready source for splicing a new roll to the end of the web drawn from a preceding roll. A movably mounted manually operated overhead crane 4 having depending arms 5 is used to bring fresh rolls 2 from a storage area to replace exhausted rolls on the unwind stand. The web in passing from the roll on the unwind stand passes through a guide unit 6 of any known type, past an infeed control panel 7 over a splicing unit or station 8 and thence into an infeeder 9 which can consist of known devices. The web on leading infeeder 9 passes into an infeed accumulator 11, also of a known type and which serves the usual purpose of storage of web to provide for continuous operation during splicing of web from a new supply roll. From the infeed accumulator, the web passes through web cleaning means schematically shown at 12 and thence to an infeed tension stand and web guide 13 which, as will appear herein-after, plays an important role in tensioning the web throughout the entire production line.

From the infeed tension stand, the web is threaded and passes through the various press units A, B, C, D, and E sequentially and when passing through each of these units is printed with a plurality of colors in a plurality of designs. A detailed description of the individual press

units will appear in the following description. After passing through the press unit E, which is the last press unit in the line, the web passes over and around idlers such as at 14 and into and through outfeed tension stand 15 which is identical to the infeed tension stand 13. The web then passes into outfeed accumulator 16 which is similar in construction and operation to infeed accumulator 11 and this facilitates again the continuous running of the web during splicing operations in the rewind station. The web then passes into an outfeeder 17 and thence to rewind stand 18 similar in construction to unwind stand 3, and here the printed web is wound into rolls 19 consisting of the printed web. Again an overhead crane 21 is provided for removal of the rolls 19 from the rewind stand for movement to a desired area out of the press line for subsequent operations and/or transportation.

As set forth in the introductory portion of this specification, one of the features is to provide for removal of the various cylinders from the units as also other components in an upward or vertical direction. To this end, an overhead crane 22 is movably mounted on tracks 23 spaced a substantial distance above the press units as also the second floor 24 on which there is positioned a cylinder cleaning station 25, cylinder cleaning rack 26 and the web cleaner 12 as appears more clearly in FIG. 1a. The tracks 23 extend along the entire length of the building so that the crane 22 can be used for servicing the entire production line as regards the movement of various components while leaving the area in and around the press free. Catwalks such as at 27 are provided for observation and to facilitate servicing of the various units.

Referring to FIGS. 3, 4, and 5 of the drawings, further details of the transport system including the crane 22 are shown. It will be seen that in addition to the tracks 23 which extend longitudinally above the press line, that transversely extending tracks 28 are provided for movement of the crane 22 transversely with respect to the press line to permit movement of components transversely beyond the press line. The crane is provided with two lift cables 29 in spaced relationship and carry at their lower ends hooks 31. The press cylinders or rolls such as at 32 are provided with trunnions 33 on which are secured bearings generally designated 34 with associated mechanism and include a fork 35 through which extends pin 36 for coaction with hooks 31 in an obvious manner. It will be apparent that with this arrangement, the individual cylinders as also other components of the apparatus can be raised vertically with respect to the press and moved to any desired position in the building housing the installation. Details of the press cylinders and bearings will be set forth hereinafter.

The various press units as also the infeed and outfeed tension stands are driven from drive motor 37 (FIG. 2) through a speed reduction unit 38. A main drive shaft 39 driven from the speed reduction unit 38 is operatively interconnected with drive means for the individual units 41 for the cylinders of each stand and these are identical as shown in FIG. 2. The tension rolls 42 and 43 of the infeed and outfeed tension stands 13 and 15 respectively are also driven by the single motor 37. A variable speed transmission 44 is driven from reduction unit 38 and this in turn drives speed reducer 45 with the interposition of an air clutch 46 for deactivating the drive. The shaft 48 of infeed tension roll 42 is driven by the speed reducer 45. The outfeed tension stand 15 is driven in a like manner from main shaft 39 through speed reduction unit 49, variable speed transmission 51, air clutch 52 and speed reducer 53.

As pointed out hereinbefore, these tension stands are substantially identical in construction and operation, the only difference being in a difference in the clothing or covering of the respective tension rolls with frictional materials so selected that the web will not slip on the infeed roll 42 but can slip or creep on the outfeed tension

roll when the desired value of web tension is attained so that a constant uniform web tension is achieved. In one application, it has been found that the infeed tension roll when coated with a rubber and cork composition with the outfeed tension roll 43 being covered with cork, satisfactory results can be obtained. In conjunction with the rolls 42 and 43, a plurality of individual rubber-covered trolleys 54 are used and which are rotatably carried on supports 55, the inner ends of which carry pistons 56 slidably mounted in cylinders 57. Springs 58 bias the supports to move the trolleys 54 away from contact with the web 1 passing over the tension rolls 42 or 43 but the degree of pressure can be adjusted by the introduction of fluid under pressure through conduit 59 into the various cylinders 57. The roll clothing of rubber and cork composition on infeed tension roll 42 is indicated at 61 and the roll clothing of cork on tension roll 43 is shown at 62. The variable speed transmissions 44 and 51 are of a vernier-type so that very fine increments of speed variation can be obtained. The web therefore is impressed against the driven tension roll by means of the trolleys and the slip or creep is kept to a minimum by proper initial adjustment of the draw transmission. By proper adjustment, the desired value of web tension from infeed stand 13 to outfeed stand 15 can be attained and once set for a given set of conditions, no further change is required, except for infrequent adjustment to compensate for wear of the frictional covering. This serves to maintain accurate registration of the plurality of printing units to give proper and consistent repeat length of the printed image as also to keep the web tracking accurately through the press. Without adequate control of tension, acceptable printing results cannot be achieved no matter how precise and well-conceived the printing units themselves may be. The present invention provides the means for establishing and maintaining a precise web tension in a multi-unit or color gravure printing press.

The foregoing description has referred to the general over-all arrangement of the press of the invention. Reference is now made to FIGS. 8-10 inclusive which show in more detail the various press units and passage of the web therethrough. The stands include side frames 63 supported on press unit base rail 64, and the units are substantially enclosed by casings or covers generally indicated at 65. Each of the units includes, generally speaking, a press section 66 and a dryer section or assembly 67. Rotatably mounted within the press section are the operating cylinders for the printing. These include engraved cylinder 68, off-set cylinder 69 having a rubber cover 71, and an impression cylinder 72. Each of these cylinders as is well understood in the art, is necessary for off-set gravure printing. These cylinders are substantially enclosed within the cover of the frame for safety and cleanliness. Access to the upper portion of the press section is effected by means of a cylinder cover 73 pivotally mounted at 74 adapted to be raised to the elevated position shown in broken lines at 73a in FIG. 8 by means of cable 75 operatively associated with a winch arrangement generally designated 75a (FIGS. 9a-9b) from which extends shaft 76 having on its end exteriorly of the casing, a sheave 77 over which is entrained an endless chain or the like 78. By manipulation of chain 78 in an obvious manner, the cover 73 can be raised or lowered to give access to the press section.

For some applications, it is desirable that the off-set roll be replaced by a flexographic roll and under such circumstances it being desirable to prevent an ink drying-in situation from arising, there is provided a blotter roll 79 which is rubber covered as at 81 (FIG. 10). This blotter roll in a lowered inoperative position rotates in an ink solvent contained in a transversely mounted ink solvent pan 82. The engraved cylinder 68 is mounted in fixed position with respect to the side frames by means of bearing assembly 34 secured in fixed supports 83 in the frame 75 (FIG. 19). The off-set roll and impression cylinder as

also the blotter roll and the supports therefor are carried and interconnected with a linkage system generally designated 84 in FIG. 8 and shown in more detail in FIG. 19. This linkage system generally is operable to control coaction between the off-set cylinder and the engraved and impression cylinders as also actuation of the blotter roll, and for moving the off-set roll into and out of engagement simultaneously with respect to the engraved cylinder and impression cylinder. Details of construction and operation of this portion of the apparatus will be set forth hereinafter.

An ink fountain assembly generally designated 85 is incorporated in the unit for coaction with the engraved cylinder for transfer of printing ink to the surface of the off-set roll, and subsequently to the web. A doctor blade assembly 86 is utilized having a doctor blade 86a for coaction with the engraved cylinder in a known manner. The structure and operation of the doctor blade assembly will be described in detail hereinafter. Adjustment means for controlling doctor motion and action are provided externally of the unit at 87 and adjustment means are also provided at 88 for control of the linkage system 84 to adjust the cylinder impression and blotter roll assembly.

FIGS. 8 and 10 clearly show the disposition of the engraved cylinder, the off-set (or flexographic) cylinder, and the impression cylinder with relation to the stand. The web 1 enters the press stand below a cross walk 89 in front of the unit with the arrangement permitting an operator to check or service the unit without interference from the web travel path. The web then passes over an idler roll 91 beneath a scanner head 92 which operates to control running register by coaction with indicia placed in the selvage of the web in the first print unit of the press. A scanner adjustment mechanism is shown at 93 to preset the scanner head depending upon the width of the web being processed so as to insure picking up the indicia thereon. The web then passes under a tension sensing roll 94 of a tension roll assembly 95 which consists of arm 96 pivotally mounted at 97 which rotatably mounts the tension sensing roll. The free end of the arm 96 is connected with a hydraulic cylinder 98 which is operatively connected into a hydraulic circuit in the unit and operates in such manner as to maintain a certain predetermined downward pressure on the end of the arm, which in conjunction with the weight of the tension roll will provide proper tension in the web passing through the unit. In the case of web breakage and/or slackness, a pressure drop in the line will occur and cause automatic shutting down of the entire press. Each of the press units incorporates such mechanism which are in series so that breakage or excess slack at any place will shut down the machine. The web 1 passes substantially vertically from the tension sensing roll 94 to and between the nip between off-set cylinder 69 and impression cylinder 72 where the printing takes place. Thereafter, the web continues upward and is visible to the operator for a distance indicated at 99 just prior to the lower edge 101 of the dryer enclosure. The web then passes over idler roll 102 upwardly over plate 103 into the drying area, and on up and over a top web idler roll 104 where it is turned downward for its approach to the discharge end of the dryer. The downward run of the web takes it through the main drying section 67 over web idler roll 105 thence around lower web idler roll 106 where it resumes a substantially horizontal path under the cross walk of the next stand, and thus on through a duplicate tour of such stands.

Any individual ones of the units or stands can be inactivated and bypassed, and the travel of the web in so doing is shown in dotted lines at 10a where it passes over idler roll 91 and down under lower idler roll 106 without passing through the unit. This arrangement of the passage of the web permits unobstructed access to vital elements of the press without cutting or removing the web which is of importance mainly for frequent pat-

tern changes. Also this arrangement, as pointed out hereinbefore, when the press is operated as an off-set gravure press permits removal of the cylinders from overhead by using the overhead crane. Access is also readily available to the doctor blade mechanism and engraved and flexographic cylinders which can be removed upwardly by the crane, and the arrangement also permits a continued tensioning of the web in the absence of running of the machine during this interchange of rolls etc.

The arrangement of the various components of the individual stands and all of the stands in the press permits a minimum of web lead from one impression to the next which is significant in order to obtain and maintain acceptable longitudinal and cross-wise register with a minimum of down graded goods. The arrangement of the various rolls and cylinders which govern the web travel through a unit also provides a good ratio between web exposure within the ink dryer to total lead and insures adequate dryer capacity. The disposition of the cylinders also results in a practical arrangement from the standpoint of approximating a complete enclosure surrounding the cylinders which is desirable for reducing the ink dry-in problem and yet permits ready and convenient means of opening thereof for overhead access as described above.

The dryer assembly or section 67 is also unique and has proven very effective in conjunction with the web path to effect substantially 100% drying. The dryer assembly includes a front dryer section 107 and a drying hood section 108. A substantially closed walk-in compartment is arranged within the unit and has portions of the walls thereof formed by sliding glass doors at 111 to permit an operator to view the web from within the unit with a compartment 112 provided for idler roll 105. A ceiling 113 extends across the top of compartment 109. The front dryer section 107 has the lower edge 101 in close proximity to the travelling web after passing by the visible area at 99, a transverse chamber 114 is provided in the upper forward corner of the front dryer section having a plurality of extended slots or openings 115 in the lower surface thereof. This chamber is in communication with an exhaust duct 116 associated with an exhaust blower (not shown) to exhaust air and vapor fumes from the drying section, and the unit generally. A slotted pipe or tube 117 extends transversely across the unit below the chamber 114 and into which is directed a stream of hot air for the purpose of drying the web. The slots in the tubes 117 are indicated at 118 and are formed with sheet metal lips which direct the stream of hot air to the web. An inlet conduit for the drying hot air is shown at 119 which connects into the tube 117.

The hood 108 includes an inlet duct 121 connected to a source of hot drying air under pressure and an outlet duct or exhaust 122. The duct 121 extends completely across the width of the hood but has formed therein downwardly inclined passageways 123 in proximity to both sides of the unit. The downwardly inclined passageways 123 communicate with chambers 124 at each end which are sealed off from the exhaust duct but into which enter or open the respective ends of tubes 125 transversely extending and in a vertical array as shown in FIG. 10. These tubes 125 have the lipped slots similar to 118 and designated 126 so that the heated drying air passes from inlet duct 121 through both downwardly inclined passageways into the various tubes for subsequent impingement on the web. A further chamber 127 is formed between the end walls defining the downwardly inclined passageways 123 and this chamber contains the tubes 125. A plurality of slots are formed in the lower surface of exhaust duct 122 opening into chamber 127 so that the heated air from tubes 125 is vented through the slots into the exhaust duct.

It will be seen that with this arrangement, the areas surrounding the cross pipes or tubes are open to the ex-

haust ducts. The entrance to the dryer embodies the principle of first exhausting for an appreciable distance along the web to remove vapors or the like which will be drawn off from the ink before a blast of heated air tends to form a retarding film on the surface of the ink and is subsequently followed by application of the first hot air stream from tube 117. This first stream of hot air is again followed by a considerable exposure to exhaust. Then during the final passage downward to the exit of the dryer, the web is exposed in rapid succession to streams of hot air alternated by exhaust. This drying system has proved extremely effective.

The ink fountain assembly can best be understood by reference to FIGS. 10 and 11. Spaced transversely with respect to engraved cylinder 68, there are formed arcuate shaped supports 129 terminating in circular depressions 131. A secondary ink pan 132 of an arcuate configuration and having a handle 133 on the forward end thereof is slidably engaged with arcuate shaped supports 129 for support thereof. The arrangement is such that a source of ink is readily available to the engraved cylinder being immersed therein and the pan is readily slideable forwardly along the arcuate slot for ultimate removal from the unit subsequent to opening of the ink fountain door 134 which is pivotally mounted at its lower end or otherwise secured for complete removal. The shape of the pan 132 at its forward end is such as to seat in the circular depression for proper positioning thereof. Ink is introduced under pressure from a source of supply, not, shown, by ink pump 135 (FIG. 9b) through piping 136 which connects into ink intake line 137 at the front edge of pan 132 and which has openings therein which cause a spraying of ink under pressure as indicated at 138 on the surface of the engraved roll. Overflow of ink in excess of that which can be held by the secondary pan occurs at the open rear or where slots or openings have been provided, and this overflow is indicated at 139. This flow is into primary ink pan 141 which has an opening 142 which communicates with ink outlet piping 143. Proper precautions are taken, in a usual manner, to have proper conditions for the ink such as viscosity, color etc., but which forms no substantial part of the present invention. This arrangement of the secondary or auxiliary ink pan which hugs the perimeter of the engraved roll and to which, through the ink header or ink intake line 137, a constantly fresh ink supply is provided results in sufficient immersion for the roll without containing a great volume of ink as would otherwise be necessary with a conventional reservoir. The surplus supplied by the ink pump via the header overflows the secondary pan to be recollected within the primary pan and ultimately is returned by gravity to the pump. The ready removability of the secondary pan facilitates clean up since it may readily be replaced by a clean pan and the one removed cleaned at leisure.

For the purpose of fire protection, a very effective CO₂ fire extinguishing system is incorporated in each unit. Heretofore, in the art, the usual method of protection consisted of stringing several CO₂ nozzles somewhere in front, or overhead, or partly both, of the press portion containing the ink fountain. The present press which is designed for full access to the front and from the top, precludes placing the nozzles in this manner which just by themselves might defeat the concept of accessibility of the unit.

There are two areas of hazard in a press unit of the present design, namely, the ink fountain coating with the engraved roll, and the solvent solution fountain associated with the blotter roll. In essence, this problem is overcome by dividing these two fountains with a hollow partition closed at the bottom to form a plenum chamber and into which the CO₂ nozzles open. Upon release therefore, according to the present construction, the gas can be directed over the liquid in both fountains.

Referring more in detail to FIGS. 10 and 11 of the drawings, the rear wall of primary ink pan 141 is ex-

tended to form a partition or dividing wall at 143 and the front wall 144 of ink solvent pan 82 forms a second spaced dividing wall or partition. The members 143 and 144 together form a hollow partition which is closed at the bottom by wall member 145. This structure creates a plenum chamber which extends transversely across the width of the unit. A plurality of CO₂ nozzles 146 open into the plenum chamber and are connected through conduits 147 to a source of CO₂ gas under pressure. A baffle or deflector 148 in the shape of an inverted L angle is positioned above the open top of the hollow partition in spaced relation with the upper edges thereof. Control of actuation of the CO₂ system can be by means of rate of rise elements or manual control means can be incorporated and preferably both. Such means are not shown in the drawings.

A plurality of the nozzles 146 extend across the width of the machine and upon actuation the CO₂ will first flood the plenum chamber at the base of the hollow partition and then pass up through the partition, striking the deflector and thus spreading the gas over the liquid in both fountains. This system is extremely effective being directly in the zone of potential fire hazard and is completely removed from the access areas.

In the upper portion of the front of the unit, there is a transversely extending heat accumulator hood 149 (see FIGS. 10 and 9a). A conduit 151 connected to a suitable source of CO₂ gas under pressure extends within this hood and has a plurality of CO₂ nozzles 152 connected thereto. Heat responsive control means and/or manual means (not shown) can be used to actuate this portion of the CO₂ system for flowing of the gas over and down the front portion of the machine.

Provision is also made by means of a CO₂ conduit 153 connected into a plurality of CO₂ nozzles 154 as shown in FIG. 10 to flow CO₂ gas into the region of the upper idler roll around which the web passes.

It is usual practice when using gravure type presses, to provide automatic register control devices for the presses.

Such devices normally consist of certain interrelated electronic units to produce suitable electrical impulses which initiate action of a mechanical or hydraulic device to automatically effect an adjustment of the printing cylinders so as to reach or maintain printing register in the direction of web travel. Heretofore, many types of register control devices have been utilized such as a hydraulic motor arranged to act upon a differential element of the press drive to affect a correction and other types, a motor causes the main propelling worm of a worm and gear type drive to shift to bring about the desired shift. Sometimes a compensator is used instead of shifting the printing cylinder. Such a compensator affects the length of web lead between the various press units and is completely unrelated to the press drive although it accomplishes register correction. This latter, however, tends to upset the register of any remaining units of the press whenever a correction is made for any one unit.

In order to accomplish the desired result, and particularly in relation to the combination off-set gravure-flexographic press of the present invention, a shifting worm register control is utilized of a unique character. The adjustment in the present press affects all three cylinders namely, the engraved cylinder, the off-set cylinder and the impression cylinder, or when the unit is being utilized as a flexographic press then the flexographic also.

As will appear, the mechanism is of extreme simplicity in construction and is readily dismountable. A minimum of parts are required and eliminates the usual sliding sleeves and stuffing boxes. The mechanism also includes means for limit control to prevent shifting of the worm used beyond the limits for which it is designed, and indication means as to the amount of shift.

Referring now to FIG. 38 of the drawings, a register control mechanism is there disclosed and consists of a unit drive case 200 suitably mounted and which, as will

be readily understood, is directly transversely aligned with a press unit and the shafts for the various cylinders. The main drive shaft 39 extends into the case and is journaled in suitable thrust bearings 201, 202. Couplings 203 connect this portion of the main drive shaft with the remainder in an obvious manner. The drive shaft for the engraved cylinder is designated 204, the drive shaft for the offset cylinder 205 and the drive shaft for the impression cylinder 206. These shafts are journaled in bearings such as at 207, 208 in FIG. 39. A drive clutch gear 209 is slidably mounted on shaft 39 by means of a sleeve at 211 and has integrated therewith a hand adjustment bevel gear 212. An internal drive gear hub 213 is secured on shaft 39 by spline 214 and lock screw 215, and carries internal drive gear 216. Drive clutch gear 209 as will be apparent from the drawings, is slidable on shaft 39 for which purpose a clutch shifter yoke 217 is operatively associated with an end of the drive clutch gear 209 and the gear is rotatable with respect thereto due to bearings 218, the position being maintained by bushing 219. A clutch shifter arm 221 is operably engaged in a slot 222 in yoke 217 mounted on shaft 223 which extends externally of the casing. This relationship is shown in FIG. 41 where the shaft 223 is operatively connected with an actuating lever 224 as will be explained hereinafter.

An elongated drive case bearing and support housing is mounted in drive case 200 and is designated 225, and as shown in FIG. 40 is secured to flanges 226 in the casing at spaced intervals therealong. A lower portion 227 is detachable from the remainder of the unit to permit insertion of various bearings and mechanisms therein. An end of the drive case bearing 225 is screw threaded internally at 228. Rotatably mounted within the drive case bearing there is a unit drive worm shaft 229 on which the worm thread portion 231 is formed on a sleeve and which also mounts a unit drive gear 232 which is in mesh with unit drive clutch gear 209, and as will appear hereinafter, slidably engaged with respect thereto. At the opposite end of the shaft, there is a circular register adjusting gear 233 rotatably mounted on bearings 234 so that the shaft is free to rotate therein. This bearing, however, is mounted on a reduced shaft portion and secured by means of an end collar 235 so that no relative axial displacement between the shaft and the adjusting gear can occur. It will be noted that gear 233 is screw threaded 45 engaged on the exterior thereof with the screw thread 228, and additionally, the outer periphery of adjusting gear 233 has gear teeth 236 formed therein. The free end of the adjusting gear 233 is peripherally grooved and a position indicating arm 237, which is pivotally mounted by shaft 238, has a nose extending into the slot and the shaft extends externally of the casing as will appear hereinafter.

The worm thread portion 231 is in meshing engagement with a drive worm shaft gear 239 splined on drive shaft 205 for the off-set roll and which serves to drive this shaft from the main drive shaft 39. Drive gears 241, 242 and 243 respectively, for the engraved cylinder shaft, off-set cylinder shaft and impression cylinder shaft respectively are splined on the shafts, and are in driving engagement one with another. Thereby all shafts and the respective cylinders are geared together and driven from the common main drive shaft through drive gear 216, drive clutch gear 209, drive gear 232, worm 231 and worm shaft gear 239. A register drive shaft bearing and housing 244 is mounted in a wall of the drive case 200 as seen in the left of the figure and has rotatably mounted therein a circular register drive shaft 245 having secured at its inner end a circular register gear drive 246 which through an opening in case bearing 225 is in engagement with the gear teeth 236 on adjusting gear 233. The outer end of shaft 245 is operatively associated with a reversible hydraulic motor 247 which, through a valve arrangement 248 is operated in one direction or another from a source of fluid in the circuit which, through appropriate electrical connections schematically represented at 249, is connected to a scanner

unit reading indicia on the travelling web, and indicating an in or out of register condition either leading or lagging to control operation of motor 247 in one direction or the other and additionally, the amount of rotation. This in turn 5 imparts to adjusting gear 233 a rotative movement through register gear drive 246 and this in turn by coaction of the threads 228 and the threads on the adjusting gear will positively move shaft 229 in one direction or the other and thus force the worm to move axially either to the left or right. This, by coaction between the worm and drive worm shaft gear 239, will advance the cylinders or retard them over and above the rotary motion imparted from the line shaft. The worm is made deliberately longer than usual to permit this motion without disturbing the normal 10 running relationship between the worm and worm gear. This shifting of the worm then results in momentarily increasing or decreasing the angular speed of the worm gear hence effecting a corresponding relative change of angular 15 position of the cylinders.

The threaded adjusting gear 233 is of a sufficient length 20 to cover the range of adjustment and lends itself ideally to the driving by a simple spur pinion such as gear drive 246.

Means are also included to limit the extent of movement 25 or shifting of the worm beyond the limits for which it is designed and this is incorporated with the position indicating mechanism and shaft. Reference is here made to FIGS. 40 and 42. The shaft 238 has secured thereto a pointer and actuator arm 251, the point of which coacts 30 with a scale 252 and dependent upon translational movement and position of the shaft 229 will serve to indicate externally how much movement has occurred and where the worm is presently positioned. Limit switches 253 and 254 are connected into an appropriate circuit in the machine and when movement of the worm shaft 229 has taken place to a desired limit, within limits of the worm, this will be reflected by movement of the pointer arm 251 which will actuate either switch 253 or 254, which in turn will act to positively stop operation of hydraulic motor 247 to prevent further shift of the worm and then appropriate action must be taken by the operator to bring the mechanism back within approximate register positions.

The device also includes means for manual adjustment of registry, and this consists of a clutch mechanism operable for shifting the drive clutch gear 209 out of engagement with the internal drive gear 216. This is possible because of the sliding relationship of drive clutch gear 209 with respect to unit drive spur gear 232 and being slidable on shaft 239. This movement results from a shift of clutch shifter arm 221 through shaft 223 which is actuatable by lever 224 secured thereto. The shaft 223 is suitably journaled in a bearing mount 256 as will be seen from FIG. 43. As a precautionary measure, the lever 224 can never be operated to engage or disengage the drive clutch gear while the mechanism is operating. To this end, a locking cylinder 257 is mounted on the frame and connected into a low pressure hydraulic circuit in the machine. This locking cylinder has a pin 258 actuatable 45 thereby into an extended position into and through an opening 259 in the housing and an opening 261 in arm 224. A spring biased pin 262 is secured in the end of lever 224 and the end thereof adapted for engagement in opening 263, also provided in the frame. In operation, it is necessary to first shut down the machine and subsequently when pressure has bled sufficiently from locking cylinder 257 the pin 258 is manually displaced inwardly 50 to clear the arm 224 and then upon outward manipulation of the spring biased pin 262 to disengaged position, the lever and associated clutch shifter arm can be rotated. This results in movement of drive clutch gear 209 through the shifter yoke and clutch shifter arm to a position wherein internal drive gear 216 and drive clutch gear 209 are disengaged. This movement in turn will cause engagement of bevel gear 264 on shaft 265 with hand adjustment bevel gear 212. Hand wheel 266 upon rotation will then 55

manually adjust the position of the gear 239 in an obvious manner. This manual adjustment can be used for initially setting for registration and/or obviating conditions which are beyond the limit of the automatic registry mechanism. Before returning to automatic operation, it is of course necessary to again shift the clutch in the opposite direction to disengage the manual and engage the automatic intercoating mechanisms.

It will be noted that the arm 224 has three positions for coacting with the pin 258. FIG. 44 shows a neutral position wherein there is no mating of either set of gears and the partial openings or grooves at opposite sides are for locking the clutch in one or the other positions dependent upon whether a manual or automatic registry function is desired.

In the lower right-hand portion of the figure there is shown a doctor motion shaft bearing and case generally designated 267 secured in the side of the casing. A doctor motion worm gear shaft 268 is rotatably mounted therethrough, and carries at its inner end a doctor motion worm wheel which mates with a worm gear connected to shaft 204. The worm wheel is designated 269 and the worm gear 271. A hand wheel 272 is operatively associated with the shaft 268 for adjustment of a doctor blade motion to control the throw and movement. The remainder of the doctor blade mechanism is not shown in this figure and is not necessary to an understanding of the register adjustment mechanism hereinbefore described.

As pointed out in the specification hereinbefore, in the arrangement of cylinders as taught by the present invention, one desirable characteristic is to be able to move the off-set roll into or out of printing engagement and this likewise would apply to the flexographic roll if substituted for the off-set roll. The present invention ideally provides a mechanism and linkage system for supporting the various cylinders that a single pair of hydraulic cylinders can operate to hold the off-set or flexographic cylinder in operating position in contact with the inking roll and with the web as it passes through the impression nip as well as shift this cylinder from impression to the throw out position. Means are also provided whereby adjustment of the various impressions can be effected without affecting other positions or settings and the ends of individual cylinders can be adjusted independently.

The mechanism also includes the blotter roll which is so arranged that when desired, this roll will move during impression throw out to contact the flexographic cylinder and/or off-set cylinder.

It will be noted that the engraved roll or inking roll remains stationary at all times and this makes possible a stationary contoured ink pan as explained hereinabove. This cylinder according to the invention is driven at all times when there is ink in the press either when printing or idling, and facilitates the use of a doctor blade arrangement which is substantially stationary other than to oscillate or to be angularly moved but which does not require a subsequent readjustment due to movement of the inking roll such as in other types of presses. These aims are all accomplished by moving only the off-set cylinder to regulate the various impressions or pressures between the various cylinders.

The mechanism for so supporting, moving, and adjusting the cylinders will be more readily understood from FIG. 19 and following. This linkage system was generally designated 84 in FIG. 8 of the drawings but details are not shown therein. Referring now specifically to FIG. 19, the trunnions 275 of impression cylinder 68 and their associated bearing assembly 34 are supported in fixed supports 83 in the machine and secured therein by means of cap members 276 secured by cap screws 277. The cap is provided with the fork 35 and pin 36 to permit removal of the rolls as discussed in connection with FIGS. 4 and 5 since the cap members and associated bearing assemblies are integrated and removable with the rolls from the supports.

Impression roll support arms 278 are pivotally mounted at 279 and at the upper ends are provided with bearings 281 to support trunnion 282 of impression cylinder 79. Plates 283 maintain the bearing in position. The impression roll is pivotal about the point 279 with a range of movement of approximately two inches to permit easier threading up of the machine and cleaning of the impression roll. The mechanism for moving this roll will be described in detail hereinafter. An impression lever 284 is pivotally mounted in the frame at 285 and which serves a multiple function with respect to carrying the blotter roll and serving to move the off-set roll into and out of printing position. To this end, a pivot is carried substantially at the end of the straight portion of the lever 284 as shown at 286a which serves to pivotally support a cradle 286 which serves as a bearing seat for the off-set cylinder bearing assembly, the trunnion of this off-set cylinder being designated 287. As before, the bearing and bearing support are separable, the bearing support at 288 being carried by the cradle 286 and the bearing being provided and coupled with the lifting member 35, 36 to permit removal of the roll from the support. The other end of the cradle is bifurcated at 288 and supported on a bearing shoe 289 carried on pin 291 which is mounted in the frame by means of eccentric hubs for rotation. An eccentric shaft lever 292 is secured to pin 291 by a rivet or pin 293 and adapted to cause rotation of pivot pin 291. The lower end of lever 292 has a bifurcated end 294 engaging over pin 295 carried on the end of ink impression lever 296 movably mounted on fixed pivot 297. The opposite end of ink impression lever 296 is operatively associated with an impression adjustment shaft 298 in screw threaded engagement for relative movement therebetween. This shaft at its upper end carries a lug 299 adapted for engagement by a handle such as at 301. This shaft also carries in screw threaded engagement therewith, an impression indicating pointer 302 which coacts with scale 303 on the front of the machine (FIG. 9). When it is desired to adjust the nip pressure between the off-set roll and engraved roll, the shaft 298 is turned which results in movement of arm 296 which through movement of eccentric shaft lever rotates pin 291 and due to the eccentric relationship of the pin and the hubs, will result in upward or downward movement of the off-set roll with respect to the engraved cylinder to increase or decrease nip pressure therebetween without any appreciable change of the nip setting between the off-set cylinder and the impression cylinder.

A hydraulic cylinder 309 is pivotally mounted at 311 on bracket 312 and has its piston rod pivotally connected at 313 to impression lever 284. This cylinder 279 is double acting and in operation serves to pivot the impression lever upwardly or downwardly about its pivot. A nose 314 on the impression lever has an adjustable stop 315 thereon which is engageable with an abutment 316 on the end of lever 317 which is pivotally mounted on the fixed pivot 297. Lever 317 at its free end is in screw threaded engagement with impression adjustment shaft 318 which carries in screw threaded engagement therewith a pointer 319 for coacting with scale 321 on the face of the machine (FIG. 9a) to indicate impression adjustment. This shaft is also provided with a lug 322 which permits turning of the same for adjustment of the off-set cylinder at the impression nip, and governs the pressure thereat. It is to be understood that this adjustment can be either coarse or fine and vernier scales such as at 323 are provided for this purpose.

Adjustment of shaft 318 serves to pivot lever 317 which, by engagement with stop 315, will rotate arm 284 about pivot 285. This results in angular movement of pivot 286a to vary impression nip between the impression cylinder and the off-set cylinder without any appreciable change of the nip setting between the off-set cylinder and the engraved cylinder.

The lower off-set end of impression lever 284 carries

a fixed bearing 304 in which is mounted trunnion 305 for blotter roll 30. The trunnion passes through a slot 306 in side frame 63 as is shown in FIG. 21. Accordingly, movement of impression lever 284 will serve not only to move the off-set roll but also the blotter roll. The lower end 307 of lever 284 has an adjustable stop member 308 adapted for coacting with the hub of lever 296 to limit the upward movement of the impression lever as will appear hereinafter.

In operation, other than for the adjustments discussed above, when it is desired to raise the off-set cylinder or flexographic cylinder from operative to inoperative position, the cylinder 309 is activated to raise the impression lever 284. This lever then pivots around pivot 285 and serves to raise blotter roll 30 together with pivot 286a and therefore cradle 286. The pivot 286a will move in an angular direction due to being pivoted about pivot 285 and this movement will simultaneously remove contact of the off-set cylinder with respect to impression cylinder 72 and engraved cylinder 68. At the same time and dependent upon the adjustment of blotter roll 79, contact will be made therebetween and the off-set or flexographic roll due to the fact that the blotter roll will move a greater distance per amount of movement of lever 284 than will the off-set or flexographic roll due to its pivotal mounting at 285 in the cradle. During such movement of the off-set roll, the bifurcated portion 288 will permit a sliding with respect to the shoe 289. It will accordingly be seen that a single movement effects simultaneous removal of contact between the off-set or flexographic roll with respect to the other cylinders in an effective manner and so serves at the same time to engage the blotter roll for the desired end purpose.

By reference to FIG. 20 there is shown an adjusted position of various of the elements described in connection with FIG. 19. In FIG. 20 the hydraulic cylinder 309 has been actuated to extend the piston rod and to move impression lever 284 about its pivot in an upward direction. It will be seen that the off-set cylinder is now disengaged from contact with the engraved cylinder and that the blotter roll is now in contact with the off-set or flexographic cylinder. In this view, the impression cylinder has been moved to an inoperative position by virtue of being pivoted together with arm 78 about pivot 279. The adjustable stop member 308 is now in engagement with the lower portion of lever 317 which serves as a stop means for the upward movement of impression lever 284.

The mechanism associated with the impression cylinder permitting the same to be moved away from the off-set cylinder for cleaning and threading operations will be more clear from a consideration of FIGS. 24-29 inclusive. In the forgoing description, with reference to the lever system mounting the various cylinders and their operation, the discussion has been limited to a single side of the machine. In actuality, the various lever arms are duplicated on either side of the machine in an obvious manner to properly support and control the cylinders and their operation. The impression cylinder support arms 278 which are pivotally mounted on pivots 279 are in fact interconnected by means of tubes 324 having flanges 325 fixed to the arms 278 so that movement of arm 278 on one side of the machine is correlated with a corresponding arm on the opposite side. In like manner, the pivot 285 consists of a rod extending between the side frames and having splined thereon the impression lever 284 as shown in FIG. 26. This insures a positive interrelationship of the arms on either side of the machine for proper action of the cylinders. A split bearing member consisting of a lower bearing portion 326 supports a tube 327 which is fitted over rod 285 in spaced relation therefrom and which terminates at the inner side of the bearing, and is secured by means of a removable cap portion 328 together with

cap screws 329 so that this tube constitutes a non-rotatable mount for the latch mechanism. The latch mechanism is generally designated 331 and includes an eccentric hub portion 332 having a bore 333 therethrough. The bore 333 is adapted for mounting on the tube 327 and is rotatable with respect thereto. The hub portion 332 has raised bosses 334 which are also eccentric as is the eccentric hub portion but of smaller dimensions. A latch handle 335 extends from the eccentric hub portion for manipulation of the latch mechanism. Split brackets are mounted over tube 327 on either side of the eccentric hub portion of the latch mechanism and are secured together by means of screws such as at 337. These screws mount the brackets non-rotatably with respect to the tube 327. The upper ends of the brackets extend beyond the eccentric hub portion 332 as also the eccentric raised bosses as shown in FIG. 26 and are provided with arcuate slots 338. The upper end of arm 278 has a bore therethrough at 339 above which the end of the arm is slotted at 341. An eccentric shaped pin 342 has its main body portion inserted through the bore 339 and the trunnions thereof extend through the arcuate slots 338 in the brackets as shown in FIG. 25 and FIG. 26. The eccentric shaped pin has a groove 343 into which engages a set screw 344. The purpose of the eccentric pin 342, is, as will appear hereinafter, to align nip contact between the impression and off-set cylinders. A squared end 345 is provided on pin 342 to permit adjustment thereof. The upper ends of the split bracket portions 336 have bores therethrough at 346 (FIG. 27) through which the shaft 347 of a hand wheel assembly passes and which shaft is in screw threaded engagement with a portion of the bore in one side of the bracket. Thimbles 348 are loosely mounted over the shaft 347 and which are in engagement with the sides of eccentric hub portion 332 adjacent to the raised bosses 334. This hand wheel assembly serves to lock the lock mechanism or handle in either an upward or downward direction as desired. The top end of arm 278 is provided at its inner face with a groove 349 into which the eccentric hub portion 332 is adapted to extend. In the position shown in FIG. 25, the handle 335 is in a position wherein the impression cylinder is in locked position and in operative contact with the off-set cylinder. The initial setting of either end of the impression cylinder is controlled by adjustment of the eccentric shaped pin 342 which coacts with the eccentric hub to govern positioning of the impression cylinder since this eccentric pin serves as a stop in conjunction with the arcuate slot. In like manner, if the handle is rotated to the left when viewing FIG. 25, then the impression cylinder will be permitted to drop by gravity to a position removed from contact with the off-set cylinder with the hub portion of the eccentric riding in the groove 349. This mechanism therefore, permits adjustment of the nip alignment between the impression and off-set roll and additionally serves as a means to move the impression cylinder away from the off-set roll for either cleaning or threading purposes.

FIGS. 13a, 13b, 14 and 15 present details concerning the mount and drive of the various cylinders, as also the means for axial registration thereof. FIGS. 30a, 30b, 31 and 32 must also be considered in conjunction with the following description. The engraved roll or cylinder is driven from drive shaft 204 through a modified Oldham coupling 351, the off-set cylinder 69 is driven from shaft 205 through a modified Oldham type coupling 352 whereas the impression cylinder 72 must have a different type of drive means due to the fact that it can be moved out of engagement with the off-set cylinder as hereinbefore pointed out. The drive for this cylinder from shaft 206 includes a straight coupling 353 attached to shaft 206 and into which is fixed a stub shaft 354 which is rotatably supported in bearing 355 supported in the covering in a known manner. A stub shaft 356 which is a continuation of stub shaft 354 enters within the cover area and

has a sprocket wheel 357 secured thereto. This stub shaft 356 then passes through a bearing 358 mounted in side frame 63 and attaches to a first portion 359 of a modified Oldham coupling. An intermediate member 361 of the Oldham type coupling mates with the first one and has slide members 362 off-set at exactly 90° to one another. These in turn mate with a third portion of the Oldham type coupling 363 which is secured to the trunnion 282 of impression cylinder 72. A chain 364 is entrained around sprocket 357 and as shown in more detail in FIGS. 14 and 15, passes between idler sprockets 365 and thence around sprocket wheel 366 attached to blotter roll 79 which as shown, through the medium of bearing 304 is rotatably supported in arm 284 and movable with respect to the side frame. Accordingly, when impression cylinder 72 is moved to an inoperative position for cleaning or threading the blotter cylinder 79 will continue to be driven through the chain even though there is relative movement therebetween. The Oldham type coupling permits such movement as also the alignment of this roll with respect to the others.

The drive side of the machine is shown in FIG. 13a and as described above. The work side of the machine is shown in FIG. 13b and it will be seen that the trunnions of the engraved and off-set rolls extend through openings in side frame 63 and are carried in bearing assemblies 34 such as previously described. Associated with the ends of the engraved and off-set rolls are axial alignment adjustment means generally designated 367 and 368 respectively. The trunnion 282 of impression cylinder 72 and the trunnion of blotter roll 79 are mounted substantially as hereinbefore described with respect to the linkage system.

The drive means and axial register adjustment means as applied to off-set roll or cylinder 69 will be more readily apparent from FIGS. 30a and 30b of the drawings. The trunnion extends through an opening in the side frame 63 and is supported in a bearing assembly 34 as hereinbefore described. The stub end of the trunnion extends beyond the cover 65 and has provided therein a peripheral groove 369 adjacent the end thereof. A frame extension 371 is secured about this stub end. A split saddle 372 including a lower saddle portion 373 and a removable cap 374 engages over the stub end and the cap has a peripheral inwardly extending rib which engages in the peripheral groove 369, this rib is shown at 375 and when the members 372 and 373 are secured together, the trunnion is fixed to the saddle as will be apparent. Stub shaft 376 passes into the interior of a hollow hub 377 having a hand adjustment wheel 378 thereon. A bearing 379 is interposed between the interior of the hub and the stub shaft, and a collar threaded on the end of the stub shaft maintains the bearing in position.

A nut 382 having tangs thereon is mounted in the housing extension and the tangs are engaged in slots such as at 383 in cap 374. This nut is captive in the sense that it can float vertically but is prevented from rotating. The nut is internally threaded and in engagement with threading 383 on the inner end of hub 377. In operation therefore, upon turning of handle 378 the thread portions in the nut and on the hub will act to transversely displace the trunnion 287 and accordingly the cylinder 69, as will be readily apparent.

The opposite end of the roll or cylinder while being supported in substantially the same manner, is connected to the drive means through an Oldham type coupling and thence to the drive shaft 205. This is shown more clearly in FIG. 30b. A saddle member 384 surrounds the lower portion of the end of the shaft which has peripheral groove 385 therein and a detachable cap plate 386 has a peripheral rib 387 engageable in the groove to fix the relative positions thereof. Plate 388 of saddle member 384 constitutes an end plate of a modified Oldham type coupling. This is provided with a groove for coaction with a vertically disposed slide member on the intermediate coupling

member 389. The intermediate coupling member 389 also includes a slide member 391 disposed at right angles to the preceding mentioned one, and this is slidably maintained in groove 392 of the third member 393 of the Oldham type coupling which is secured to drive shaft 205 for the off-set cylinder. The vertically disposed slide arrangement between the first and second members 388 and 389 can be seen by reference to FIG. 32 of the drawings. A guard 394 is secured to side frame 63 and is of a curvilinear nature. This can, if desired, be nylon lined or the like and being positioned below the saddle 384 as a safety precaution since when the detachable cap 386 is removed, the saddle 384 by virtue of the vertical slide in the Oldham type coupling will be free to drop and might otherwise result in injury. A casing 395 surrounds the Oldham type coupling and the open end thereof is closed by means of a detachable ring 396 and a flexible seal member 397.

The modified Oldham type coupling is shown in greater detail in FIG. 37. The modification mainly resides in the third member of the coupling 393 which is hollowed out and into which there is slidably inserted a circular member 399 having a bore 401 therethrough. A plurality of circular holes 402 are provided in the inner face of member 393 and the circular member 399 is provided with a corresponding number of holes partially therethrough at 403. Spiral springs 404 are engaged between mating ones of the holes and tend to bias the member 399 out of the hollow interior of member 393. An additional set of holes 405 are also provided in the circular member 399 but opening outwardly to the opposite face from those of 403. Spring retaining plates 406 are secured to the outer end of member 393 and have slight recesses therein. Springs 404 disposed in the holes 405 are retained therein by these spring retaining plates 406. Shaft 205 is inserted in the bore in circular member 399 and a drive spline and key generally designated 407 serve to operatively interconnect the circular member 399 with the interior of member 393 to transmit drive through the coupling to the trunnion of the cylinder while at the same time permitting axial adjustment of the cylinder. The springs and arrangement result in a self-centering feature while at the same time permit of the axial adjustment of the cylinder.

The present invention, due to the possibility of moving the off-set or flexographic roll from operative to inoperative position selectively is adapted for skip printing procedures to, for example, print a cross border on a traveling web without interfering with tension of the web in the over-all unit and actuation of such skip printing can be automatically accomplished and timed. The preferable technique in such skip printing is, during normal running of the press, to remove the off-set roll in one stand from operative position for a given time interval until the proper length of web has been printed before overprinting on a border to define a transverse edge or end of a rug for example and to bring the off-set roll into engagement at the proper time to print the border. A standard off-set roll can be used for this purpose with a properly patterned engraved roll, and since all rolls are continually running in synchronism the engraved cylinder will impart the requisite pattern to the off-set cylinder for printing of the border. In accordance with a modification of the invention, however, a modified form of off-set cylinder is provided. Referring to FIG. 16, there is shown such a modified off-set cylinder.

This includes a shaft 410 on which the cylinder is rotatably journalled as hereinbefore described. The cylindrical steel cylinder 408 again bears a rubber covering 409 but only over a portion of segment of the periphery. The position shown in full lines of the raised rubber covering or the like 409 shows the off-set roll in inactive raised position. When the proper time has arrived for printing of the cross border, the cylinder 408 will have rotated to a position whereby the segment 409 will be in the position shown in broken lines at 409a and the roll or cylinder will have been lowered so that the

periphery thereof will be in the position indicated at 408a and accordingly as the printing operation continues, ink having been placed on the segment 409 by the engraved cylinder, will print a cross border on the web 1 at the desired place. Subsequently, when the segment 409 has completed its printing operation, the off-set cylinder will again be raised into inoperative position.

Means can be included at various places in the press to so activate the off-set roll or cylinder to effect such a skip printing operation. One type of mechanism which can give the desired results is shown in FIGS. 17 and 18. A hub secured on the impression cylinder drive shaft 354 is indicated at 409 and mounts thereon a circular plate 411 in an adjustable manner by means of slots 412 and screws 413. The disc or plate has an aperture 414 in the outer edge thereof. An ultrasonic sensing element such as a "Sonac" element generally designated 415 is mounted on the press for coaction with the aperture 414 in the plate. When the aperture in the plate or disc is in line with the Sonac units, an electrical signal is induced which in turn actuates a solenoid valve in the hydraulic system to cause the off-set cylinder to be raised or lowered as required. This automatic control parallels, without detracting from, the already existing controls for raising or lowering the off-set cylinder. This timing disc could be installed on a shaft other than the impression cylinder but this is immaterial since the shafts rotate in perfect synchronization. A counter element or device is schematically shown at 416 into which the leads from the Sonac unit sends a signal. When printing cross borders at positions longer than the periphery of the off-set cylinder, the mechanism is set so that the off-set roll is not moved into printing position until the proper number of revolutions of the plate have been made. Assuming that a cross border has just finished printing, then at the precise moment that the active segment 409 of the off-set cylinder clears the web, the timing plate or disc matches with the Sonacs and sends a signal to raise the cylinder. The signal first actuates the electro-mechanical counter which records the impulse, and subsequently sends out its own impulse to raise or lower the off-set cylinder which follows immediately. This raising action, and subsequent lowering of the cylinder takes place while the active segment 409 of the off-set cylinder is rotating over the top, from the web toward the engraved cylinder. Then exactly one revolution later, the Sonac units send a second signal to the counter. This second signal can then cause the cylinder to be lowered while the active segment of the cylinder is rotating over the top toward the engraved cylinder. The cylinder reaches full down position just before the active segment of the off-set cylinder and the engraved band of the engraved cylinder meet at their nip. It will be apparent that between the first and second signals under some operating arrangements, one whole revolution will be made with the cylinder in the up position and hence a cross border which would have been printed if the cylinder had remained down will be skipped.

As was pointed out in the objects of the invention, there is also incorporated a novel doctor blade holder susceptible of such mounting and operation as to be substantially trouble free, susceptible of easy mounting and operation and removable vertically from a stand of the press. The doctor blade assembly of the present invention utilizes a blade holder of superior rigidity and which is supported at the ends only when in the press and still will not deflect beyond the limits tolerable for this type work. The present doctor blade assembly is so designed and mounted that it provides a safe operation susceptible of easy and accurate adjustment and which can be readily and easily removed from the machine. FIG. 48 shows generally the location of the doctor blade assembly 86 as applied to the present machine. The structure includes a main axis 501 about which the entire doctor blade mechanism, which is movably mounted, is adapted to rotate. Mounting on the press, however, is effected by means of circular

plates 502 which include bolting flanges 503. The frame 63 as shown in FIG. 19 has a circular cut-out portion 504 formed therein in which the circular plate 502 is seated around substantially 180° of its periphery with the bolting flange in engagement with the inner wall of frame 63. 5 A plurality of bolts 505 secure the plate 502 to the frame. The plate includes a fixed extension 506 in which is mounted a bearing 507 secured in position by means of cap 508. The ends of the main axis 501 pass through the bearings 507 and it will be noted that the axis is slidably transversely in these bearings. Seals are provided at 509. 10 A reduced portion of extension 506 carries a crank head 511 to which is operatively connected piston rod 512 which is driven from doctor blade hydraulic adjusting cylinder 513 as will appear hereinafter. A holder support 514 is rotatably mounted by and on the main axis 501. One of these holder supports is located at each side of the doctor blade assembly as will be seen by reference to FIGS. 51a and b. A tube 515 extends between the 15 holder supports 514 at either side and is integrated therewith by welding. This tube 515 surrounds main axis 501. A second tube 516 similar to 515 extends between and is integrated with holder support 514 by welding or the like. A rod 517 extends through the tube 515 passing through linear anti-friction bearings and having the stub 20 ends 518 extending outwardly into and beyond the circular plates 502 at either side of the machine. The linear anti-friction bearings are designated 519 in the drawings. An arcuate slot 521 is cut in each of the circular plates 502 through which the ends of rod 517 extend and which permit travel of the doctor blade assembly in an angular path of travel. The crank 511 has a bifurcated end into which the stub shafts 518 extend. The rod end of piston rod 512 is attached to the stub shaft 518. It will be seen that actuation of the piston rod due to the disposition of 25 the connection point with respect to the main axis will cause a rocking of the entire assembly between the holder supports as indicated by arrow 522 in FIG. 50. The end 523 of axis 501 opposite to that shown in FIG. 51b is likewise supported in a bearing 524 in holder support 514. The arrangement is otherwise similar with the exception that the free end of the shaft is connected to an end of 30 doctor blade motion arm 526 which as is more clearly seen in FIG. 9b interconnects this end of axis 501 with the doctor blade reciprocating mechanism. The doctor blade motion arm is connected to axis 501 through an eye and bearing assembly 527 having a live center to permit relative rotation between the axis and the doctor blade motion arm. A curvilinear shield and cross tie member 35 528 extends between the circular plates 502 and is bolted to the bolting flanges 503 thereof. A seal cover 529 is attached to tube 515 by a flange 531. The upper ends of holder supports 514 have bores therethrough in which bosses 532 of a saddle member 533 are inserted, and are 40 rotatably adjustable therein. A securing cap and screw arrangement generally designated 534 secure the boss in the bore. The lower end of the saddle has a plurality of interconnected holes 535 therein adapted for coacting with a plurality of threaded holes 536 in holder support 514. 45 Screws or the like 537 passing through and into the holes are used to adjust the angular disposition of the saddle with respect to the holder support. A support shelf 538 is adapted for supporting a mating lower surface of a trunnion 539 at each end of the blade holder 541. A yoke 542 passes around and over trunnion 539 as seen in FIG. 52 of the drawings. The saddle has bores 543 extending into the opposite transverse sides thereof. The lower ends of the yokes are provided with holes 544. A bolt 545 has a sleeve portion 546 and a threaded end 547, and extends into the bores 543 and through a smaller opening centrally interconnecting the bores. A sleeve 548 passes over the threaded end 547 into the bore and is secured by means of a collar and set screw generally designated 549 with the other end being positioned by the head on the bolt. The smaller opening interconnecting the bores is 50 55 60 65 70 75

screw threaded and the threaded portion of the bolt is in screw threaded engagement therein. A fiber lock plug operatively engaged by a set screw passes through a threaded opening in the base of the saddle shelf and as shown in FIG. 52 this combination generally indicated 551 serves to lock the bolt in position.

Set screws 552 pass through the sides of the yoke for engagement with the sides of the trunnion 539 and are provided with lock nuts 553. The upper surface of the trunnion is provided with an insert 554 in the nature of a steel button and a set screw 555 passes through the top of the yoke and is in engagement with this button 554. Inwardly of the trunnions, the blade holder 541 is provided with lifting ears 556 having openings therethrough for the insertion of lifting hooks from the overhead crane. Extending between lifting ears 556 is a tube 557 which is integrated with the ears and which constitutes the main body portion of the blade holder. A blade support shelf 558 extends along the length of the tube and is formed integrally therewith. A flexible doctor blade of thin steel or the like 86a is carried on shelf 558 and is secured thereon by means of cap 559 which is secured in place by a plurality of bolts 561.

As hereinbefore described, the hydraulic piston 513 acting through piston rod 512 and crank 511 adjusts the relative position of doctor blade 86a with respect to the engraved cylinder. The doctor blade 86a can be set at any desired relation with the cylinder by means of the doctor motion adjustment device 87, the lower end thereof constituting a stop by abutment with the crank 511 as shown in FIG. 49.

The angular relationship of the blade 86a with respect to the cylinder is adjustable by placing the locking screw 537 in different ones of 535 and 536 in any combination thereof which gives a large degree of adjustability.

It will be obvious that the construction of the yoke and its association with the trunnions of the blade holder permits of easy and flexible adjustment of the blade with respect to the engraved cylinder.

The mechanism for adjusting the amount of throw of the doctor blade will be described with reference to FIGS. 45 and 46 of the drawings. An eccentric 562 is mounted on the end of shaft 268 and splined thereto at 563 for rotation therewith. A flange 564 having gear teeth thereon is provided on the inner end of eccentric 562. A second eccentric 565 is mounted on eccentric 562 and has an internal ring gear 566 secured thereto engageable with the teeth on eccentric 562. A recess 567 is provided in the outer end of eccentric 565 in which a spiral spring 568 is seated. A cap plate 569 secured by screws into the shaft 268 and eccentric 562 maintain the springs in position and bias the two sets of gear teeth into meshing engagement. The hand wheel 272 is formed with a circular flange and is attached to eccentric 565 by means of a hub extension thereon and screws 571. A hub 573 of the doctor blade reciprocating arm 525 is rotatably journaled on the exterior of eccentric 565 by bearings 574. An extension 575 is provided on the hub, the end of which is inserted between guides 576 of guide bracket 577 supported on the casing 200 of the main drive unit 41. The purpose of this guide bracket and guide arrangement is to prevent lateral movement of the blade reciprocating arm and hub. In FIGS. 45 and 46, the eccentrics are arranged for the greatest throw movement of the doctor blade reciprocating arm. If it is desired to change this setting, the handle 272 is grasped and pulled outwardly with respect to shaft 268. Due to the space provided between the flange of eccentric 565 and the inner end of hub 573, eccentric 565 and the internal ring gear secured thereto can be displaced to the position indicated by dotted lines at 578. This results in disengagement of the two sets of teeth which permits relative rotation of one eccentric with respect to the other and in an obvious manner this will change the throw of the blade reciprocating arm.

Manifestly minor changes in details of construction can be effected without departing from the spirit and scope of the invention as defined in and limited solely by the appended claims.

I claim:

- 5 1. In a rotary printing press an engraved cylinder, an impression cylinder spaced from said engraved cylinder, an offset cylinder interposed between said engraved and impression cylinders and in operable printing relation therewith, drive means for said cylinders including a main drive shaft, an internal drive gear secured to said drive shaft, an external toothed drive clutch gear slidably mounted on said drive shaft and having the teeth thereon engageable with the internal drive gear, an auxiliary shaft rotatably mounted adjacent said main drive shaft, a pinion gear on said auxiliary shaft in mesh with said drive clutch gear, a worm gear secured on said auxiliary drive shaft, a worm wheel operatively connected to the drive shaft for said offset cylinder and meshing with said worm gear, main cylinder drive gears on the drive shaft for each said cylinder in meshing engagement one with another for simultaneous drive of all said cylinders, a bearing unit rotatably mounting said auxiliary drive shaft having at one end thereof an internally screw threaded portion, a circular register adjusting gear rotatably secured on said auxiliary drive shaft, but fixed against displacement, said adjusting gear being externally toothed and having screw threads formed in said teeth engaging with said screw threads in said bearing, said auxiliary drive shaft and gears thereon being slidably mounted in said bearing parallel with said main drive shaft, a circular register drive gear in mesh with the teeth on said circular register adjusting gear and means responsive to improper registry of a web being printed by said cylinders operable to rotate said register gear drive in one direction or the other to thereupon rotate said register adjusting gear whereby through coaction of the threaded portions said auxiliary shaft will be translated coaxially to thereby rotate said offset cylinder an increased increment by coaction with said worm wheel to re-establish proper register.
- 10 2. In a rotary printing press as claimed in claim 1, said drive clutch gear having a circular bevel gear extending outwardly beyond the periphery of said clutch gear at a position spaced from the end engageable with the internal drive gear, a reduced diameter hub on said drive clutch gear extending beyond said bevel gear, a clutch shifter yoke mounted on said hub and fixed thereon against lateral movement, said hub being rotatable within said yoke, a clutch shifter arm having an end operatively connected to said shifter yoke, a pivotally mounted shaft mounting said clutch shifter arm and means for rotating said shaft whereby said drive clutch gear is slidably displaced on said auxiliary shaft to disengage the external teeth thereon from said internal drive gear, the teeth of said drive clutch gear and said pinion gear being in slidable engagement to permit relative movement thereof.
- 15 3. In a rotary printing press as claimed in claim 2, a rotatably mounted shaft operable for manual adjustment of said drive clutch gear, a bevel gear on an end of said shaft, means for rotating said shaft, said bevel gear being engageable with said bevel gear on said drive clutch gear subsequent to disengagement of said drive clutch gear and said internal drive gear whereby said worm gear can be manually rotated to thus manually adjust the position of said offset gear.
- 20 4. In a rotary printing press as claimed in claim 1, indicia sensing means in said press adapted to sense register indicia printed on a traveling web, motor means operatively connected to said register drive gear and means operable by said indicia sensing means for rotating said circular register drive gear in one direction or the other through said drive means therefor.
- 25 5. In a rotary printing press as claimed in claim 4, a

lever in engagement with said circular register adjusting gear, a pivotally mounted shaft mounting said lever, a pointer member mounted on said pivotally mounted shaft, which means engageable by said pointer and operable upon movement of said pointer to predetermined extremities in one direction or the other to deactivate the main drive means for said printing press.
